Specification for Design.

Patented Oct. 29, 1918.

Application filed July 12, 1918. Serial No. 244,666. Term of patent 14 years.

To all whom it may concern:

Be it known that I, TRUE M. AVERY, a citizen of the United States of America, residing at Glens Falls, in the county of Warren and State of New York, have invented a new, original, and ornamental Design for a Connector for Antiskid-Chains, of which the following is a specification, reference being had to the accompanying drawing, in which—

Figure 1 is a view in perspective of a

connector for antiskid chains embodying my new design.

Fig. 2 is a plan view of the same, and
Fig. 3 is a front elevation of the same.

I claim:—

The ornamental design for a connector for antiskid chains, as shown.

TRUE M. AVERY.
